FIRE ESCAPE

Theophilus A. Barham, Norfolk, Va.

Application May 8, 1939, Serial No. 272,507

3 Claims. (Cl. 227—30)

The device forming the subject matter of this application is a fire escape of the type in which a support, attached to the body of an operator, carries a drum upon which a flexible suspension element is wound. The invention aims to provide a brake mechanism which is spring-actuated to hold the drum against rotation, but releasable at the will of an operator. Another object of the invention is to provide novel means whereby the 10 brake mechanism may be released completely from the drum. A further object of the invention is to provide novel means whereby an operator can control the brake mechanism manually from the upper portion of the support.

15 It is within the province of the disclosure to improve generally and to enhance the utility of devices of that type to which the present invention appertains.

With the above and other objects in view, which 20 will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Fig. 1 shows in vertical section, a fire escape 30 constructed in accordance with the invention;

Fig. 2 is a cross section on the line A—B of Fig. 1, looking in the direction of the arrows 2—2;

Fig. 3 is a cross section on the line A—B of Fig. 1, looking in the direction of the arrows 3—3;

Fig. 4 is a cross section on the line 4—4 of Fig. 1.

The fire escape disclosed is made of metal, 40 and sheet metal if desired. The support or casing C is open at its upper and lower ends and includes a body 1 having a reduced neck 2, provided with opposed, integral, upwardly-extended hand grips 3, the upper ends of which are secured 45 within a transverse guide 4, of inverted trough-shape. The intermediate portion of the guide 4 carries a grommet 6, through which pays, without undue wear, a flexible metal cable 7.

The cable 7 passes downwardly across a supporting pin 8, if desired but not necessarily, the pin being held for small transverse movement in vertically-elongated slots 9 in the side walls of the casing C. The flexible element 7 is wound about the tubular hub 10 of a drum D including heads 55 11 secured to the hub, the heads being located in

close relation to the side walls of the casing C, and being cup-shaped, so as to give a good bearing for a braking instrumentality to be described hereinafter. The inner end of the flexible element 7 is secured at 12 to one of the heads 11 of the drum D. The hub 10 of the drum D turns on a shaft 23, mounted in the side walls of the casing C. The heads 11 of the drum D are engaged peripherally by arcuate brake shoes 14, suspended by hangers 15 from the supporting 10 pin 8. The hangers 15 hold the upper ends of the brake shoes 14 apart, to form a space 16, through which the flexible element 7 passes.

The lower ends of the brake shoes 14 are connected by any preferred number of strong pull 15 springs 17, and there may be four of these springs, if desired. The inner ends of outwardly-extended and upwardly-inclined links 18 are pivoted at their inner ends to the lower ends of the brake shoes 14 and have movement through 20 holes in the casing C. The outer ends of the links 18 are pivoted to the lower ends of levers 19 which, intermediate their ends, are inset, for the purpose of bringing the upper ends of the levers close enough to the grips 3 so that one grip and 25 the corresponding lever 19 may be grasped readily by a human hand. The levers 19 are fulcrumed intermediate their ends on rivets 20 or the like, carried by ears 21, struck out of the body 1 of the casing C. The fulcrum elements 20 are disposed 30 close to the lower ends of the levers 19, to give the operator a high advantage over the pull of the strong springs 17.

A yoke 22 has pivotal movement on one end of the shaft 23. The ends of the yoke 22 are inclined, and have holes receiving a girt 24, which may be buckled around the body of the wearer.

The upper end of the flexible element 7 is made fast to any accessible object. The springs 17 hold the shoes 14 engaged with the drum D. It 40 has been found, in practice, that, by means of the shoes 14 and the springs 17, the device will retain a weight of a thousand pounds. The operator lays hold of the upper parts of the levers 19 and the hand grips 3 and tilts the levers on 45 their fulcrs 20, the links 18 serving to elongate the springs 17 and ease off the hold of the shoes 14 on the drum D. The operator can descend with such speed as is desirable or expedient. If, due to excitement or any other cause, the operator releases the levers 19 quickly, the brake shoes 14 will grip the drum D under the action of the springs 17, and there is no danger, that he will descend too rapidly.

The part 4 is called a guide, because the up- 55

per ends of the levers 19 are mounted to move in it. Especial attention is directed to the fact that the grips 3 and the upper parts of the levers 19 are disposed at the top of the fire escape. When 5 the device is attached to the human body, the operator, most naturally, reaches upwardly and can grasp the parts 3 and 19, to control the brake mechanism.

As to the reason why the slots 9 that receive 10 the supporting pin 8 are elongated vertically, it will be noted that when the lower ends of the levers 19 move outwardly, the links 18 exert an upward pull on the brake shoes 14, and the pin 8 can rise a little in the slots 9. The result 15 is that the brake shoes 14 are freed from the drum D throughout its entire circumference, there being no drag on the drum, at the top thereof, or elsewhere.

What is claimed is:

- 20 1. In a fire escape, a support provided at its upper end with adjacent upstanding grips, means for attaching the support to the body of an operator, a drum journaled on the support, a flexible suspension element wound about the drum, a brake mechanism carried by the support and coacting with the drum to limit the rotation thereof, and levers operatively connected to the brake mechanism and controlling the operation thereof, the levers being fulcrumed on the support and extending upwardly alongside the grips, in close enough relation thereto so that one lever and the corresponding grip can be received in one hand of the operator.
- 25 2. In a fire escape, a support provided with upstanding grips, means for attaching the support to the body of an operator, a drum journaled on

the support, a flexible suspension element wound about the drum, brake shoes disposed about the drum, means for connecting the upper portions of the brake shoes to the support for limited vertical movement, spring means coacting with the 5 shoes to cause them to engage the drum, levers fulcrumed intermediate their ends on the support and extended upwardly alongside the grips in close enough relation thereto so that one lever and the corresponding grip can be received in one hand of 10 an operator, and links pivoted to the lower ends of the shoes and to the lower ends of the levers, the links being so inclined as to lift the shoes when the lower ends of the levers move outwardly.

3. In a fire escape, a support provided at its upper end with upstanding grips, means for securing the support against the torso of an operator, a drum journaled on the support, a flexible suspension element wound about the drum, a 20 brake mechanism carried by the support and coacting with the drum to limit the rotation thereof, and levers operatively connected to the brake mechanism and controlling the operation thereof, the levers being fulcrumed on the support and 25 extending upwardly alongside the grips, in close enough relation thereto so that one lever and the corresponding grip can be received in one hand of the operator, and a guide connecting the grips adjacent to their upper ends, the levers being 30 slidably received in the guide, the flexible element passing through the guide, the guide being spaced from the support to give access to the grips and the levers.

THEOPHILUS A. BARHAM. 33
